UNITED STATES PATENT OFFICE.

LOUIS L. BROWN, OF NEW YORK, N. Y., ASSIGNOR TO THE FOUNDATION COMPANY, A CORPORATION OF NEW YORK.

APPARATUS AND METHOD FOR BUILDING FOUNDATIONS AND THE LIKE.

1,159,171.

Specification of Letters Patent.

Patented Nov. 2, 1915.

Application filed May 7, 1914. Serial No. 836,933.

To all whom it may concern:

Be it known that I, LOUIS L. BROWN, a citizen of the United States, residing in the city, county, and State of New York, have 5 invented certain new and useful Improvements in Apparatus and Methods for Building Foundations and the like, of which the following is a specification.

In building foundations by the pneumatic 10 method it is customary to sink a number of caissons and to fill them with concrete so that they serve as piers to carry the weight of the superstructure. It is desirable in many cases to make a continuous wall of 15 such caissons or piers around the lot and then to excavate within the lot for the cellars of the building. It has been found difficult to form a water tight connection between the adjacent piers so as to exclude 20 water from the excavation.

My invention provides a new method by which this can be done with comparatively little difficulty and no danger to the workmen.

25 The invention provides a method and apparatus which are also applicable to other purposes, as hereinafter stated.

The accompanying drawings illustrate a method and apparatus embodying the invention.

Figure 1 is a plan of the adjacent portions of two caissons or piers during the sinking of the same; Fig. 2 is a horizontal section of the same; Fig. 3 is a side elevation 35 of the lower portion of one of the caissons with the addition of a plow which is connected to the other caisson, the figure being a section on the line 3—3 of Fig. 2; Fig. 4 is a section of the lower part of the two adjacent caissons on the line 4—4 of Fig. 2; Fig. 5 is a side elevation similar to Fig. 3 showing the position of the parts during 40 the operation of forming the joint; Fig. 6 is a vertical section through the concrete-receiving grooves during the operation of forming the joint; Fig. 7 is a vertical section 45 through the earth-receiving grooves during the operation of forming the joint; Fig. 8 is a horizontal section of two united caissons; Fig. 9 is section of the same after certain optional finishing steps.

Referring now to the embodiment of the invention illustrated the caissons A may be of any usual or suitable design, being made

generally of solid concrete with a working 55 chamber B (Figs. 4 and 6) at the lower end and a shaft or shafts through the center for the passage of men and materials and with an air lock at the upper end of each shaft for maintaining a supply of compressed air 60 in the working chamber. The ends of the caissons are molded with vertically extending grooves C which are to be used for the introduction of a connecting body of concrete between the adjacent caissons and 65 which in the finished structure serves to tie the adjacent caissons or piers to each other. On the end faces of the caissons they are provided each with a vertically movable plate D which closes the groove C during 70 the sinking of the caisson, but which is pulled out after the caisson has sunk to permit the placing of a key or body of concrete from the groove C of one pier across the intervening space between the two piers and 75 into the groove C of the adjacent pier. The form illustrated for the plate D is one which is in common use in steel sheet piling, a sort of bulb E being provided on the edges of the plate and fitting between a pair of plates 80 F and G, these being riveted on an I-beam H mounted at either side of the groove C. At its lower end the I-beam and attached parts are supported upon a channel J which with the angle K constitutes the cutting edge 85 of the caisson, the groove C having its inner face inclined outwardly from about the level of the roof of the working chamber to a point just above the cutting edge so as to permit the working chamber to be made of 90 the full length of the pier at its base.

At each side of the groove C, and separated therefrom by one of the I-beams H, is a groove L, which may be considerably shallower than the groove C. The sides of 95 each of the grooves L are composed of one of the I-beams H and a corner post M carrying a grooved pair of plates F and G similar to those carried by the I-beams. Each groove L is closed by a plate or sheet N 100 having a bulb E on each edge engaged between the plates F and G. Thus the plates N which close the side grooves L are adapted to be raised, the same as the plates D which cover the central groove. The purpose of these grooves L is to provide a space, when the plates N are raised, for receiving a portion of the earth which lies between the

caissons approximately equal in volume to that lying between the opposite plates D, so as to ease the removal of such earth in the manner hereinafter described from between 5 the plates D in order to introduce the key of concrete across between the grooves C.

For removing the earth from between the opposed plates D, I use a device consisting of a plow or wedge shown best in Figs. 4 10 and 5 and indicated as a whole by the letter O and having opposite downwardly inclined face portions P meeting in a point in the center with vertical stiffening ribs on the outer edge and with downwardly extending 15 tail pieces Q at the two ends, and formed with an inner flange or plate R which is bolted to the outside face of the plate or sheet D at its lower end, so that the tail pieces Q extend below the lower end of the 20 plate D. The plow O is bolted to the plate D after the caisson is sunk. For this purpose it is only necessary to excavate a slight distance outward and around the cutting edge, the plow being then introduced from 25 the working chamber to the outside of the plate and bolted thereon. Upon the adjacent face of the next caisson the plate D is extended downward below the cutting edge and a plow O' is applied thereon in the same 30 way as the plow O and at a point below the latter, and this plow O' is made smaller so that it lies below and within the plow O as indicated in Fig. 5.

In sinking the caissons the plates D and 35 N close the grooves C and L throughout their height, so that the caisson as it is sunk will occupy all of the space excavated and prevent the flowing of earth into such grooves, which might endanger the safety of 40 adjoining buildings. When the two caissons have been sunk, however, and the plows attached as above described, the several plates D and N on the adjacent ends of both caissons are raised together, and at the same 45 time concrete is introduced into the two grooves C as by means of pipes C', Fig. 6, or in any other suitable way; and as the plates are raised the supply of concrete is maintained at a point above the lower edges 50 of the plates D. The plows as they are raised force the earth to the sides in the manner indicated by the arrows in Fig. 5, their action being made very easy by reason of the vacant space provided by the grooves 55 L as the latter are opened by the simultaneous raising of the plates N. At the same time the body of concrete S introduced into the grooves C is forced out beyond the sides of the caisson and under the rising plows 60 so that it forms a connecting body or key as indicated in Figs. 6 and 7. The arrows S' in Figs. 5 and 6 indicate the flow of the concrete. The earth flowing into the grooves L is indicated at T in Fig. 7 and the arrows 65 T' in Figs. 5 and 7 indicate roughly the di-

rection of flow of the earth. The movement of the concrete S out beyond the plates D may be assisted by rammers or other means and workmen may go down into the grooves C to assist in the operation, if necessary.

70

The portion K of the cutting edge is continuous across the end of the caisson, but the portion K is cut away at the center as shown in Figs. 3 and 5 to give the workmen easy access to the back of the plate D for insertion of the bolts to fasten the plow as in Fig. 4. The lower ends of the plates N are bolted to the portions K of the cutting edge during sinking and are easily disconnected from within the working chamber when the 80 plates are to be raised. The arrangement of the posts or beams H and M and the guides thereon hold the plates D and N out beyond the cutting edge, as indicated by the space between D and J in Figs. 1 and 2. To prevent the escape of air around the cutting edge and up through this space and through the open grooves C and L a packing should be provided as shown at W in Fig. 4 between the cutting edge and each of said 90 plates D and N. Such packing may be hemp, oakum or the like and may be removed before the raising of the plates.

85

After sinking the line of caissons and completing the keys S the space within may 95 be excavated with little or no leakage of water through the line of caissons. The earth T in the exposed portion of the grooves L and between the face lines of the caissons (Fig. 8) may then be removed at 100 one side of the key S, as well as the corner posts M with their guides F, G, and the resulting space may be filled with brickwork U or concrete as shown in Fig. 9, practically 105 extending the masonry in the inner face of the wall and making such face continuous and smooth wherever exposed by the excavation. The entire face may then be coated with a finishing coat as of waterproofing cement V.

110

The two plows O and O' are made to have considerable play between them because it is not always possible to sink the caissons accurately to the desired line. Sometimes one caisson will be found several inches out of line with the adjacent one at the bottom and farther removed from or closer to the adjacent one than intended. The use of two plows permits the widening or narrowing 115 of the space between the caissons without impairing the efficiency of the apparatus as long as the caissons are close enough together to keep the plows overlapping. The lateral play between the two plows indicated in Fig. 5 permits the bottom of one caisson to be considerably out of line with the other without affecting the operation. The tail pieces Q on the plows prevent the earth 120 displaced from above by the rising of the plow from working around to any material 125

130

extent under the ends of the plow and permits the concrete to extend laterally substantially to the line of these tail pieces Q.

In many cases it will be practicable to 5 use a single plow on one of the plates D, lifting both plates D together and introducing the concrete either through one groove C alone so that it flows under the plow and into the opposite groove C or introducing the concrete through both grooves C simultaneously. In some cases also it may be possible to make a groove in only one caisson and only sufficiently deep to permit the introduction of pipes for supplying concrete 10 under the plow to form a body of concrete extending between the substantially flat end faces of the caissons; having a plate D and plow only on the caisson having such shallow groove.

20 Instead of two separate plows O and O' I may in some cases use a single plow consisting of a suitably shaped block of wood, metal or other material fastened to both plates D and therefore perfectly closing the 25 space between such plates.

The caisson or pier illustrated is molded of solid concrete. The side mold boards X may be sunk with it or may be removed, whichever is more economical in the special 30 circumstances. The ends are molded by means of boards located between the end posts M and beams H for the side grooves and by means of suitably shaped boxes between the two beams H for the central 35 groove; such boards and boxes being removed before the insertion of the removable plates and the sinking of the caisson.

The earth-receiving grooves L are preferably made of just sufficient capacity to receive the quantity of earth which is to be 40 removed by the plows and replaced by the concrete key. They may, however, be made larger or smaller according to circumstances and my invention contemplates the omission 45 of such grooves where the conditions are such that the earth can be compacted or shoved aside or partly or entirely lifted above the surface (as where the depth is slight and the material light) by the plows 50 without the provision of a special space to receive it.

The plows may also be made of various designs and proportions according to the conditions encountered; for example, a plow 55 with only one inclined side may be used and the earth forced all in one direction, in which case only a single earth-receiving groove L may be provided. In either case the inclination of the plow may be varied 60 within wide limits and the tail pieces thereof may be extended or shortened or entirely eliminated. Various methods may be used for attaching the plows and various designs may be used for the plates which carry the 65 plows and for the means of fastening and

guiding said plates, as well as the plates which cover the earth-receiving grooves and their guiding and supporting means.

The process may be applied also to other cases than the joining of the piers of building foundations. It may be applied in fact wherever a continuous structure is to be made by the sinking of successive adjacent caissons; and wherever it is desired to introduce a body of concrete upon the outer face 75 of a caisson, cofferdam, pile or similar structure. For example, in underpinning the wall of an old building a succession of piles may be sunk adjacent thereto and may be provided with plows upon their outer faces, 80 that is the faces which are under the wall, and with means for introducing concrete from the opposite side of the pile under its lower edge and thus under the plow; the raising of the pile and the continuous introduction of concrete resulting in the production of a body of concrete extending from the desired level up nearly to actual contact with the lower edge of the wall; the space 85 above this concrete and below the body of the wall being easily accessible to finally insert a filling of concrete or the like.

Though I have described with great particularity certain specific embodiments of my invention yet it is not to be understood 95 therefrom that the invention is restricted to the particular embodiments disclosed. Various modifications in the details and in the arrangement of parts of the apparatus and in the several steps and in the order of 100 steps in the process may be made by those skilled in the art without departure from the invention.

What I claim is—

1. The method of placing a body of concrete in the earth which consists in providing a plow at the required depth adapted when raised to displace the earth in its path and raising said plow and introducing concrete to take the place of the earth displaced 105 by the plow.

2. The method of placing a body of concrete in the earth which consists in providing a plow at the required depth adapted when raised to force the earth to the side 115 and raising said plow and simultaneously introducing concrete under it to take the place of the earth displaced by the plow.

3. The method of placing a body of concrete in the earth which consists in providing a plow at the required depth adapted when raised to force the earth to the side and raising said plow and providing an empty space at the side of said plow for permitting an easy movement of the earth 125 displaced thereby and introducing concrete beneath the plow as it is raised to take the place of the earth displaced thereby.

4. The method of joining adjacent caissons which consists in providing a plow at 130

the required depth upon the outer face of one of said caissons, raising said plow and thereby displacing earth between the caissons and introducing concrete beneath said plow as it is raised to take the place of the displaced earth.

5. The method of joining adjacent caissons which consists in providing a plow at the required depth upon the outer face of one of said caissons, raising said plow and thereby displacing earth between the caissons sidewise and introducing concrete beneath said plow as it is raised to take the place of the displaced earth, and providing an empty space at the side of said plow for permitting an easy movement of the earth displaced thereby as it rises.

6. The method of joining the adjacent faces of two caissons which consists in providing on the outside of such adjacent faces a pair of plows, one mounted on each of said caissons and one overlapping the other and simultaneously raising said plows to cause them to displace the earth and introducing concrete beneath them to take the place of the displaced earth and to form a connecting body between the two caissons.

7. The method of joining the adjacent faces of two caissons which consists in providing on the outside of such adjacent faces a pair of plows, one mounted on each of said caissons and one overlapping the other and simultaneously raising said plows to cause them to displace the earth and introducing concrete beneath them to take the place of the displaced earth and to form a connecting body between the two caissons, and providing empty space for permitting an easy movement of the earth displaced by the aforesaid plows as the latter are raised.

8. The method of joining the adjacent faces of two caissons which consists in providing said caissons with grooves in said adjacent faces for receiving concrete and with vertically movable plates closing the outer faces of said grooves, and providing means on the lower ends of said plates for displacing earth between them as the plates are raised and raising said plates and simultaneously filling said grooves with concrete and introducing the same under the ends of said plates to bridge the space between the opposite grooves and to form a body of concrete entering both said grooves and constituting a key between said caissons.

9. The method of joining the adjacent faces of two caissons which consists in providing said caissons with grooves in said adjacent faces for receiving concrete and with vertically movable plates closing the outer faces of said grooves, and providing means on the lower ends of said plates for displacing earth between them as the plates are raised, and providing also grooves in the adjacent faces of the caissons closed by ver-

tically movable plates and adapted when opened to receive the earth displaced by the aforesaid means, and raising the several plates referred to and simultaneously introducing concrete into said first mentioned grooves and under the lower edges of the plates closing the same so as to occupy the space between the said grooves to form a body of concrete entering said grooves and constituting a key between said caissons.

10. The method of joining the adjacent ends of caissons which consists in providing a groove in at least one of said ends, closing said groove until the caissons are sunk and then opening the same and displacing earth from between the caisson ends into said groove and replacing the displaced earth by concrete extending across the space between said ends.

11. An apparatus of the character described including a plow and a supporting means therefor adapted to be sunk to the desired depth and then to be raised with the plow attached thereto to cause a displacement of the earth from the path of the plow.

12. An apparatus of the character described including a plow and a supporting means therefor adapted to be sunk to the desired depth and then to be raised with the plow attached thereto to cause a displacement of the earth from the path of the plow and means for permitting the introduction of concrete under the plow as the latter is raised, to take the place of the displaced earth.

13. A caisson or the like having a vertical groove, a vertically-guided plate closing said groove during the sinking of the caisson, and a plow adapted to be attached to the outer face of said plate, whereby the raising of the plate causes the plow to displace the earth in its path and the introduction of concrete into said groove causes the same to flow under said plow and replace the displaced earth.

14. A pair of caissons or the like having opposed vertical grooves on their adjacent faces, vertically-guided plates closing said grooves during the sinking of the caissons, and plows adapted to be attached to the outer faces of said plates and to overlap one another, whereby the raising of said plates displaces the earth between the caissons and the introduction of concrete into said groove causes the same to flow under said plow and replace the displaced earth.

15. A caisson or the like having a vertical groove, a vertically-guided plate closing said groove during the sinking of the caisson, and a plow adapted to be attached to the outer face of said plate, whereby the raising of the plate causes the plow to displace the earth in its path and the introduction of concrete into said groove causes the same to

flow under said plow and replace the displaced earth, said caisson having a second vertical groove adjacent to the first and a second vertically-guided plate closing the same during the sinking of the caisson, whereby the raising of said second vertically-guided plate opens its groove to ease the movement of the earth by said plow.

16. A pair of caissons or the like having opposed vertical grooves on their adjacent faces, vertically-guided plates closing said grooves during the sinking of the caissons, and plows adapted to be attached to the outer faces of said plates and to overlap one another, whereby the raising of said plates displaces the earth between the caissons and the introduction of concrete into said groove

causes the same to flow under said plow and replace the displaced earth, said caissons having also earth-receiving vertical grooves adjacent to the first-mentioned grooves and vertically-guided plates closing said earth-receiving grooves during the sinking of the caisson, whereby the raising of the latter plates opens their grooves to ease the movement of the earth by the plows.

In witness whereof, I have hereunto signed my name in the presence of two subscribing witnesses.

LOUIS L. BROWN.
